UNITED STATES PATENT OFFICE.

ZACHARY E. RUSSELL, OF SAUK RAPIDS, MINNESOTA, ASSIGNOR TO CLYDE W. WARREN, OF SAUK RAPIDS, MINNESOTA.

STAPLING MACHINE.

Application filed July 21, 1924. Serial No. 727,215.

This invention relates to a stapling machine and while the machine is capable of stapling many different articles, one particular use thereof is in stapling together the 5 slats at certain portions of a porch curtain formed of flexibly connected slats. In the manufacture, these curtains are made on a loom and then the slats and the molding are stapled together at the top of the curtain 10 and the slats are also stapled together at the bottom of the curtain. A longer staple is required for securing together the parts at the top of the curtain than at the bottom thereof.

It is an object of this invention to provide 15 a machine which will quickly and efficiently staple together the various parts above referred to.

It is a further object of the invention to provide a machine adapted to travel along the 20 curtain longitudinally of the slats thereof and to insert and clinch the staples at spaced points along the curtain.

It is also an object of the invention to provide such a machine which travels along the 25 curtain and staples together the parts thereof at different intervals, which machine forms the staple while in motion and stops momentarily to drive the staple.

It is a further object of the invention to 30 provide a machine which will travel in one direction along the curtain and insert and clinch staples of a certain length and which may quickly and easily be reversed and will travel in the opposite direction and insert and clinch staples of a different length.

It is thus another object of the invention to provide such a stapling machine with 35 means for guiding and progressing the same and intermittently arresting the movement thereof in definite positions.

It is a still further object of the invention to provide a stapling machine having one staple forming and driving mechanism in combination with two feeding mechanisms 45 arranged to feed, respectively, different lengths of wire, which parts are driven by one driving mechanism, means being provided for throwing into and out of operation either feeding mechanism.

It is still further an object of the invention to 50 provide a stapling machine having parts adapted to clamp the work, which parts may be adjusted to suit various thicknesses of the work.

It is further an object of the invention to

provide a staple driving and clinching mechanism having means for crossing the ends of the staples after they are driven through the material and before the same are clinched tightly in position.

It is also an object of the invention to provide a novel and efficient form of staple forming and driving mechanism including means for guiding the wire during the wire feeding and staple forming operation.

It is another object of the invention to provide such a staple forming and driving mechanism, as set forth in the above paragraph, which guiding means comprises a swinging member having a guiding groove formed 70 therein through which groove the wire swings in the staple forming operation, said swinging member being swung to one side by the movement of the staple former.

It is still another object of the invention to 75 provide such a machine, as above set forth, with various means for quickly and easily controlling the various movements and adjustments thereof.

These and other objects and advantages of 80 the invention will be fully set forth in the following description made in connection with the accompanying drawings in which like reference characters refer to the same parts throughout the different views, and in 85 which,

Fig. 1 is a view in front elevation of the machine, said view being somewhat diagrammatic;

Fig. 2 is a view in front elevation of the 90 machine showing only a portion of the guiding and progressing means, said figure being shown on an enlarged scale;

Fig. 3 is a view in end elevation of the machine as seen from the right of Figs. 1 and 95 2, the guide channels being shown in section and with some parts broken away;

Fig. 4 is a vertical section taken substantially on the line 4—4 of Fig. 3, as indicated by the arrows;

Fig. 5 is a vertical section taken substantially on the line 5—5 of Fig. 2, as indicated by the arrows, Figs. 4 and 5 being shown on an enlarged scale;

Fig. 6 is a vertical section taken substantially on the line 6—6 of Fig. 2;

Fig. 7 is a view partly in end elevation and partly in vertical section and taken substantially on the line 7—7 of Fig. 2;

Fig. 8 is a partial view in vertical section 110

taken substantially on the line 8—8 of Fig. 2, as indicated by the arrows;

Fig. 9 is a somewhat diagrammatic view partly in end elevation and partly in vertical section taken substantially on the line 9'—8—8 of Fig. 2;

Fig. 10 is a horizontal section taken on the line 10—10 of Fig. 2;

Figs. 11, 12 and 13 are horizontal sections 10 through the staple forming and driving mechanism showing the same in different positions of operation;

Fig. 14 is a view in vertical section taken on a plane indicated by the line 14—14 of Fig. 3, as indicated by the arrows;

Fig. 15 is a view in vertical section on the line 15—15 of Fig. 11, as indicated by the arrows;

Fig. 16 is a view in horizontal section taken 20 substantially on the line 16—16 of Fig. 2;

Figs. 17 and 18 are plan views of the driving plunger and adjacent parts showing the same in different positions of operation;

Fig. 19 is a partial view in side elevation, 25 as seen from the left of Fig. 9;

Fig. 20 is a partial view in side elevation of the machine, as seen from the left of Fig. 2;

Fig. 21 is a partial view in rear elevation of the machine;

30 Fig. 22 is a view partly in side elevation and partly in vertical section of the cam shaft control lever;

Fig. 23 is a partial view in front elevation 35 of the machine traversing and brake mechanism;

Fig. 24 is a view partly in side elevation and partly in vertical section of the clutch lever; and

Fig. 25 is a bottom plan view of a wedge 40 cam and co-operating parts.

Referring to the drawings, the machine, as a whole, is mounted and suspended from a pair of spaced parallel channel bars 1 having their channels facing each other. A truck 45 comprising longitudinally extending bars 2 moves between said channels 1 and has a pair of wheels 3 at each side thereof, said wheels being transversely alined at each end of said truck and supported upon fixed axles 4, the 50 longitudinal members 2 being connected to said axles by nutted yokes 5. Also secured to said bars 2 is a frame member or box 6 comprising spaced plates in which are secured the bolts or rods 7 depending therefrom in quadrilateral spaced relation and which carry at their lower ends cross bars 8^a extending endwise at each end of said frame or casing 6. Four rods 9 are threaded 55 at the upper ends and secured by nuts 9^b disposed at both sides of bars 8^a, said rods 9 passing through the bars 8^a and depending therefrom in quadrilateral relation, said rods 9, in the embodiment of the invention illustrated, being shown as rectangular in cross section. The rods 9 are secured at their lower

ends to a box or casing 8. This casing 8 forms a housing for various driving parts and a support for various parts of the machine. On top of the casing 8 a motor 9^a is disposed illustrated as of a common type of 70 electric motor. The motor shaft of the motor 9^a extends to the left, as shown in Fig. 2, and extends into a gear housing 10 being supported in suitable anti-friction bearings 11

75 in said housing. Said shaft carries a pinion 12 meshing with and driving a gear 13 mounted on a shaft 14 extending through the housing 10 and having bearings in the sides thereof, which shaft 14 also carries a pinion 15 meshing with and driving a large gear 16.

80 The gear 16 is secured to a shaft 19 journaled in a bearing formed in a hub in said gear housing and has its other end journaled in a hub 10^a projecting from the end of a substantially rectangular portion 10^b of said gear housing. Oppositely disposed beveled gears

85 17 and 18 are journaled on the shaft 19. A beveled gear 18^a is mounted on a shaft 21 supported in one side of the portion 10^b of the housing and meshes with the gears 17 and 18. A clutch 20 is splined to the shaft 19 and adapted to be moved longitudinally thereof to engage either of the gears 17 or 18, which gears have clutch teeth at their front ends, or to be disposed in neutral position between 90 said gears. It will be seen that said gears and clutch form a reversing mechanism for driving the gear 18^a in opposite directions. The shaft 21 extends through the portion 10^b of the gear housing and is provided at one side 95 thereof with a sprocket wheel 22 adapted to drive a chain 23, for a purpose to be later described. The clutch 20 is provided with the usual central groove adapted to receive the 100 prongs 24^a of a clutch fork 24 which is pivoted in lugs formed on one wall of the housing portion 10^b and has a handle portion 24^b projecting at the front side of said housing portion 10^b.

105 The chain 23 passes upwardly in an inclined direction from the sprocket 22 and passes over and drives a sprocket 25 secured to a shaft 26 journaled in anti-friction bearings 27 mounted in the sides of casing 6, said shaft projecting at the end of said casing. At the end of shaft 26 opposite the sprocket 25 is secured a crank disk 28 having a crank 110 stud 29 secured therein by a suitable clamping nut, which stud carries a roller 30 mounted on an anti-friction bearing on said stud. Said stud has an outer flange or collar 29^a thereon from which projects outwardly a central pin 29^b. The roller 30 is disposed in vertical alinement with the depending teeth 115 31^a of a rack bar 31 secured to the outer side of one of the channel members 1 and depending therefrom.

120 The casing 6 has a slide 32 mounted at one side thereof in suitable guides, which slide has hollow sleeves at each side thereof. 125

130

Threaded at their lower ends to receive bored plugs 32^c, plungers 33, having flat heads surmounted by friction plates 33^a adapted to contact the bottom sides of the 5 channel members 1, extend through said plugs and sleeves, and springs 34 surround said plungers in said sleeves and bear against plugs 32^c and shoulders formed adjacent the top of said plungers. The slide 32 is engaged at its central portion by one end of a lever 35 (see Figs. 3, 5 and 23) pivoted at its other end in casing 6, and carrying a cam roller 36 engaged by a cam 37 on shaft 26. Slide 32 is normally in its lowest position 10 but is raised by lever 35 and through springs 34 presses plates 33^a against the channel member 1. It will be noted that cam 37 is located on the opposite side of shaft 26 to roller 30 so that as the latter is traveling 15 around the end of a tooth 31^a the casing 6 will be stationary and held so by the brake or friction plates 33^a.

The parts 32 to 37 therefore form a brake mechanism adapted to engage and clamp the 20 channel bars 1 so as to hold the machine securely in stationary position between its intervals of movement.

A V-shaped bar 39 is supported from the channel bar 1 carrying the rack 31 by spaced 25 supporting members 39^a and a frame or plate member 40 is mounted on the bar 39 having secured thereto spaced rollers 41 resting on the top of said bar, said plate 40 being formed with a V-shaped groove adapted to fit over the lower edge of bar 39. The plate 40 is adapted to be held in various positions longitudinally of the bar 39 by a latch lever 42 having a square or angularly shaped socket at one end adapted to fit over the studs or 30 bolt heads on the bolts which secure the rack 31 to the channel bar 1, as shown in Fig. 1. A flat bar 43 is secured adjacent the bottom edge of the plate 40 projecting below said edge and has another bar 44 secured thereto and overlapping the bottom edge thereof, as clearly shown in Figs. 3 and 5. Another bar 45 is secured to and projects outwardly from the rack 31 at the right hand end thereof, as shown in Fig. 1, and this bar 45 also has a plate or bar 46 secured thereto and overlapping the bottom edge thereof. Both bars 44 and 46 have downwardly depending arms 44^a and 46^a, respectively, having horizontal pivots 46^b in their lower ends to which 40 are secured upwardly extending arms 51^b, respectively, said arms having a slight swinging motion against the tension of coiled springs 50 secured to their outer upper ends and to arms 44^a and 46^a. Said pivots 46^b also carry downwardly extending arms 51 and 51^a for a purpose to be later described. Arm 51^b has an inclined cam face adapted to be engaged by pin 29^b carried by disk 28.

The clutch 20 is, as stated, adapted to be moved by a lever 24, the end 24^b of which

projects forwardly from the housing extension 10^b and is pivoted to an arm 65 which is secured to the lower end of an oscillatable rod 66 supported in brackets 67 projecting forwardly from one of the rods 9. Said rod 70 70 75 80 85 90 95 100 105 110 115 120 125 130 projects forwardly from one of the rods 9. Said rod 66 is manually turned to operate the clutch by a lever rod 67 having a handle 68 slideable thereon adjacent each end. Each handle 68 is connected by a link 69 to one of two 75 80 85 90 95 100 105 110 115 120 125 130 135 140 145 150 155 160 165 170 175 180 185 190 195 198 200 205 210 215 220 225 230 235 240 245 250 55 against the lower heads of said rods or bolts. The upper block 57, however, can be depressed and the springs 58 compressed so that the rods 56 will pass downward through 5 the block 55. The block 57 has connected thereto an upwardly extending link rod 59 which is connected at its upper end to one end of an arm 60, which latter arm is connected to one end of a shaft 61 projecting 10 through and journaled in the casing 6, said shaft having at its opposite end a curved arm 62 adapted to pass beneath the depending teeth 31^a and carrying at its other end a roller 63 which is adapted to engage the bottom of the bars 43 and 45. The roller 63 normally is held at the outer end of headed stud 63^a by a spring 63^b surrounding said stud. Said roller 63 is adapted to be moved inwardly at a certain point in the travel of 15 the machine by wedge-shaped cams 43^a and 45^a on bars 43 and 44, and 45 and 46, respectively. The shaft 61 is placed under tension to hold the roller 63 against the bars 43 and 45 and to swing said roller upwardly by a 20 torsion spring 64 secured at one end of said shaft and at its other end to the casing 6, said spring being disposed between arm 62 and the end of said casing. It will thus be seen that if the arm 62 is allowed to swing 25 upwardly the shaft 61 will be rotated and rod 59 pulled upwardly so that the wedge block 54^a on the lever 54 will be depressed and the locking bolt 53 allowed to lock the cam shaft 52 to the shaft 19. The wedge 30 block 54^a may also be depressed and the cam shaft 52 locked to the shaft 19 by pressing down on the forward end of lever 54. The lever 54 also has a lug projecting from the block 54^a which forms a stop adapted to be 35 contacted by a stop lug 52^a on shaft 52 so that said shaft is stopped in a certain definite position, as will be later described.

The staple forming and handling parts, as they are operated from the cam shaft 52, 40 will be referred to with reference characters having the prefix *a*. On the shaft 52 are disposed four spaced cams *a*¹, *a*², *a*³, and *a*⁴, respectively. The cam *a*¹ engages the roller on a bell crank lever *a*⁵ having a lower slotted arm *a*⁶ received in the lower forked end of the lever *a*⁵ and connected thereto by a headed and nutted pivot bolt *a*⁷. The said fork has transverse slots in its arms through which projects a headed and nutted bolt *a*⁸ passing 45 through a hole in the arm *a*⁶. A threaded stud *a*⁹ extends through the lever *a*⁵ at the rear of its fork and has a forwardly projecting rounded lug adapted to engage in a rounded slot in the rear end of arm *a*⁶, said 50 stud *a*⁹ having a washer and a nut on each end thereof so that it may be adjusted transversely of lever *a*⁵. An angular adjustment of the lower arm *a*⁶ of the lever is thus effected. The bolts *a*⁷ and *a*⁸ may be tightened 55 after the desired adjustment is made. The

lower end of arm *a*⁶ is provided with a substantially horizontally disposed slot engaging a pin *a*¹⁰ projecting at each side of a main forming anvil member *a*¹¹ comprising a bar of rectangular cross section having its lower end disposed at a considerable angle to the horizontal. An auxiliary forming anvil member *a*¹² is disposed in front of the main forming anvil *a*¹¹ and has a rearwardly projecting portion sliding in a groove formed 70 in the front of the main forming anvil *a*¹¹ and said auxiliary anvil *a*¹² also has a lip *a*¹³ overhanging the top of the casing in which said anvil members are mounted. A plunger 75 *a*¹⁴ slides through a plug threaded into the top of the main forming anvil *a*¹¹ and has a head at lower end resting on the rearwardly projecting portion of the auxiliary anvil *a*¹². A spring *a*¹⁴' surrounds the plunger *a*¹⁴ and contacts with said plug and the auxiliary 80 anvil *a*¹². It will be noted that the rearwardly projecting portion of anvil *a*¹² is spaced a certain distance from the bottom of the groove in the forward portion of main forming anvil *a*¹¹. Upon rotation of cam *a*¹, 85 the lever *a*⁵ with its arm *a*⁶ will be oscillated and the anvils *a*¹¹ and *a*¹² successively raised.

The cam *a*² has a roller engaging therewith carried by a lever *a*¹⁵ which has an arm *a*¹⁶ at its lower end angularly adjustable relatively thereto by parts similar in all respects to the parts *a*⁷ and *a*⁹ described in connection with the arms *a*⁶ of lever *a*⁵. The lower end of lever arm *a*¹⁶ is rounded and engaged in a slot formed between two upwardly projecting portions on a staple driving plunger *a*¹⁷ having a small groove *a*¹⁸ extending across its front face, the front portion of said plunger being beveled. Plunger *a*¹⁷ has semi-cylindrical ribs along its sides at its front end 100 for a purpose to be later described. As shown in Figs. 6 and 13, the plunger *a*¹⁷ moves in a rectangular passage formed in the casing forming part of the machine frame. It will be seen that when cam *a*² revolves the lever *a*¹⁵ will be oscillated to move the plunger *a*¹⁷ forwardly and rearwardly.

The cam *a*³ has a roller engaging therewith carried by a lever *a*¹⁹ disposed at one side of the lever *a*¹⁵ and the lower end of lever *a*¹⁹ also has its lower end equipped with an adjustable arm *a*²⁰ connected thereto in the same manner that the arms *a*⁶ and *a*¹⁶ are connected to their respective levers. The bottom of said lever arm *a*²⁰ is also rounded 115 and disposed in an opening or slot formed in a former *a*²¹ having a dividing slot *a*²² of rectangular cross section at its forward end, which slot forms, in effect, arms at each side thereof, which, it will be noted, are of different widths. The former *a*²¹ is adapted to be moved forwardly and rearwardly by its lever *a*¹⁹ and will pass at each side of the main forming anvil *a*¹¹ and auxiliary anvil 120 *a*¹², as shown in Figs. 11 and 12. Said former, 125 *a*²¹, as shown in Figs. 11 and 12. Said former, 130

as shown in Fig. 14, has a V-shaped upper portion sliding in a dove-tailed groove in the casing portion a^{23} . It may be here noted that said casing portion a^{23} forms a carrying body or member for the main forming anvil a^{11} and auxiliary anvil a^{12} , and plunger a^{17} and the former a^{21} . Said portion a^{23} , as shown in Figs. 4 and 14, has upwardly extending side portions connected to and depending from the casing 8. The former member a^{21} has separate forming dies a^{25} secured therein which have slots in their side edges and which are disposed immediately adjacent the slot a^{22} . As seen in Fig. 14, these dies are provided with slots on both edges so that they may be reversed. The said former a^{21} also has inserted in the side edges of its lower rectangular portion hardened cutting plates a^{26} . The three cam levers a^5 , a^{15} and a^{19} are all provided with hubs mounted, side by side, and swinging on a shaft a^{27} secured in bosses or hubs on portion a^{23} of the frame. Each of said levers also has a rearwardly extending plunger a^{32} pivotally secured at its rear side and extending through a bushing a^{33} threaded into a rearwardly extending portion a^{34} of the casing 8. A coiled compression spring a^{35} surrounds each of the plungers a^{32} and acts to press said plunger and said lever inwardly, thus holding the rollers on said levers securely in engagement with the surfaces of the cams a^4 , a^2 and a^3 . The tension of springs a^{35} can be adjusted by screwing the bushings a^{33} inwardly or outwardly. At the right side of the lower rectangular portion of former a^{21} , as seen in Fig. 14, is a block a^{28} fixed to the lower portion a^{23} of the frame and said block has extending therethrough a hardened wire guiding tube a^{29} , the inner end of which has its plane face in close alinement with the cutter plate a^{26} and said tube forms the shear plate against which a wire is cut by said cutter plate. The said rectangular portion of former a^{21} , at its left side, as seen in Fig. 14, is engaged by a forwardly and rearwardly movable slide a^{30} mounted on a dove-tailed rib a^{31} secured to the bottom of the frame portion a^{23} . The slide a^{30} also has a hardened wire guiding tube a^{31} disposed transversely therein the inner end of which tube has its plane face in alinement with the outer edge of the other cutter plate a^{26} , said tube forming the shear plate for said cutter. As shown in Fig. 11, the front face of slide a^{30} is disposed considerably in the rear of the face of block a^{28} and a stationary block a^{63} is disposed immediately in front of slide a^{30} and bolted to the undersurface of frame portion a^{23} , said block a^{63} being of the same height and width as the slide a^{30} . The block a^{63} is provided with a narrow slot $a^{63'}$ disposed in line with the end of a swinging guiding member a^{36} . Said member a^{36} swings into said slot $a^{63'}$ when it is swung outward-

ly the movement of the former a^{21} . The block a^{28} and the slide a^{30} each have pivoted therein a swinging guiding member a^{36} having a substantially circular portion about its pivot and a laterally projecting portion having a forward substantially radial edge and an outer circumferential edge and a rear edge substantially tangential to said circular portion. Said laterally projecting portion has a narrow slot a^{37} extending therethrough of slightly larger diameter than the diameter of the wire used for the staples. Said members a^{36} , as shown in Figs. 11, 12, 13 and 15, are mounted in slots formed in the members a^{28} and a^{30} and said members normally are in the position shown in Fig. 12 and in dotted lines in Fig. 11, with the substantially radial edges thereof substantially alined with the axes of the tubes a^{29} and a^{31} . It will be noted that the members a^{36} in the respective members a^{28} and a^{30} are reversely disposed and each member has a plunger rod a^{38} connected thereto passing through a threaded bushing a^{39} and having a coiled compression spring a^{40} coiled thereabout, which springs normally press said plungers to swing the members a^{36} to their normal positions. Said members a^{36} are swung outwardly by the forward movement of the former a^{21} , as will be later described.

The frame portion a^{23} has rectangular slots formed in its opposite sides in which the sides a^{41} of the slide a^{42} move, said sides a^{41} being held in position by the side plates $a^{42'}$. The slide a^{42} has upwardly projecting portions at each side (see Figs. 8 and 10) between which are disposed cams a^{43} mounted on a shaft a^{44} extending through the portion a^{23} of the frame. Said cams a^{43} when rotated, move the slide a^{42} forwardly and rearwardly. The shaft a^{44} performs several functions and will again be referred to. The members a^{41} extend forwardly and support a frame or casing portion a^{45} adapted to support and guide the clinching parts for the staple. Said portion a^{45} comprises vertically spaced portions having a pivot shaft a^{46} secured therein on which swings a bell crank lever a^{47} . Said lever has its arms disposed outwardly and downwardly and its outwardly extending arm is pivoted by a link a^{48} to the outer end of a lever a^{49} , which lever oscillates about a pivot shaft $a^{49'}$ carried in casing 8 and which lever has an upwardly extending arm provided with a cam roller engaging cam a^4 mounted on the cam shaft 52. Lever a^{49} has a plunger a^{50} pivotally secured thereto and projecting outwardly, said plunger being surrounded by a compression coiled spring a^{60} bearing against the head of said plunger at its inner end and against a plate a^{61} at its outer end, which plate is carried on spaced threaded studs a^{62} extending outwardly from the front of casing 8. The studs a^{61} are provided with adjusting nuts at each side of said

plate so that the tension on spring a^{60} can be varied, which spring thus acts to hold the cam roller on lever a^{49} against its cam. The upper end of link a^{48} has a pin a^{50} projecting at each side disposed in an elongated slot formed in the outer end of lever a^{49} forming a lost motion connection, the upper end of link a^{48} being bifurcated. The pin a^{50} projects at each side of the link a^{48} and has vertical apertures extending therein through which pass rods a^{51} , being threaded at their upper ends and provided with nuts. The rods a^{51} have hubs at their lower ends and a headed pin a^{52} passes through these hubs through the bifurcated lower end of link a^{48} and through the end of lever a^{47} which is received in the bifurcation or fork of link a^{48} . Compression coiled springs a^{53} surround the rods a^{51} between the pin a^{50} and the nuts on said rods. The link a^{48} is also preferably made in two telescoped and threaded sections for the purpose of adjustment. The downwardly extending end of lever a^{47} is rounded and disposed in an aperture formed in a clinching anvil or plunger a^{57} (see Figs. 9, 17 and 18) which is mounted for longitudinal movement in the casing or head a^{45} . The lever a^{49} has a two-part longitudinally adjustable link a^{55} having forked ends pivoted thereto intermediate the ends of said lever, said link being pivoted at its lower end to the upper end of a plunger a^{56} adapted to move vertically in guideways formed in the head a^{45} . The plunger a^{56} has its front end beveled rearwardly at the bottom thereof to form a wedge and said beveled end is adapted to be projected into an opening $a^{57'}$ of a longitudinally movable work-contacting slide a^{54} divided at its inner end and mounted to slide in a guideway formed in the head a^{45} . The slide a^{54} has slots formed in its forward end at each side of the plunger or clinching anvil a^{57} and reversely arranged levers a^{58} are pivoted to said slide and disposed in said slots. Said levers have inwardly projecting chisel-like points $a^{58'}$ at the lower ends and are further provided with inwardly projecting lugs intermediate said ends $a^{58'}$ and their pivots and at the upper ends thereof beyond said pivots. The plunger or clinching anvil a^{57} has a forward end formed on a slight concave curve and closely in the rear of said forward end has oppositely projecting double wedged portions $a^{57''}$ immediately in the rear of which said plunger or clinching anvil has oppositely disposed depressions. At some distance in the rear of the projections $a^{57''}$ the plunger or clinching anvil a^{57} also has pointed triangular oppositely projecting portions $a^{57'''}$ and depressions are formed in the sides of said plunger at the front and rear of each of said latter projecting portions. The projecting portions $a^{57''}$ and $a^{57'''}$ are adapted to act, respectively, on the inwardly projecting lugs at the intermediate portions

and end portions, respectively, of the levers a^{58} in the movement of the plunger or clinching anvil a^{57} , as will be later described.

The wire feeding portions which feed the wire from which the staples are made will now be described and these parts will be designated by reference characters having the prefix b . The wire to be used is mounted or coiled on reels b^1 secured in brackets projecting laterally from each of the front rods 9, as shown in Figs. 1 and 2. From the reels b^1 the wire is led downward over guiding sheaves b^2 carried on small brackets secured at the outer ends of rods b^3 which, in turn, project outwardly from the ends of frame portions projecting outwardly from the sides of the frame portion a^{28} . The wire is held in alignment with sheaves b^2 by passing through guide b^3' also carried on rods b^3 . The wire also passes through an eye in an angularly adjustable member b^4 carried on dog b^{13} . The eye in member b^4 can be swung out of line with lower guide b^3' and the wire opening in dog b^{13} to give a straightening effect to the wire as it is fed through said members. A cam b^5 is secured at the right hand end of the cam shaft 52 (see Figs. 2 and 3), which cam has concentric cam tracks b^5' and $b^{5''}$. Levers b^6 are pivoted to portions of the frame projecting from the side of casing 8 and carry rollers at their upper ends, respectively, engaging the said cam tracks, the lever b^6 at the forward portion of the machine being controlled by the outer cam track and the lever b^6 at the rear of the machine being controlled by the inner cam track. The levers b^6 are moved to keep their rollers in contact with cam b^5 by compression coiled springs b^7 surrounding plungers pivoted at their forward ends to said levers below their pivots and projecting through small brackets b^8 at their rear ends, said brackets being bolted to the front and rear portions of casing 8. The front lever b^6 is pivotally connected at its lower end by a link b^9 to a wire feeding dog b^{10} . The dog b^{10} is longitudinally apertured to receive the wire and said wire passes over a series of teeth or corrugations formed on the upper surface of an open rectangular portion formed in said dog. A pawl b^{11} is pivoted in said dog above the said corrugated portion and has a lower corrugated surface adapted to co-operate with the first mentioned corrugated portion, said pawl b^{11} being mounted so that it can swing forwardly but cannot swing rearwardly past the lower corrugated portion. The feeding dog b^{10} is mounted for sliding movement on a pair of vertically-spaced rods b^{12} which have at their outer ends a stop dog b^{13} . The dog b^{13} is constructed similarly to the dog b^{10} carrying a similar swinging pawl which engages the corrugation on said dog to prevent retrograde movement of the wire as the dog b^{10} moves outwardly. The rear lever b^6 is

mounted on a shaft b^{14} extending through a hub projecting rearwardly from the frame, which shaft carries at its outer end an arm b^{15} projecting downwardly. The arm b^{15} is connected by a link b^{16} , which link extends across to the other side of the machine to an arm b^{17} , which arm is connected to a shaft b^{18} mounted in a bracket $b^{18'}$ projecting from the lower portion of casing 8 and at the rear thereof. The shaft b^{18} passes to the forward portion of the machine and has secured to its front portion a downwardly extending arm b^{19} . The arm b^{19} is reversely disposed to the lower end of the front lever b^6 and is pivotally connected by a link b^{20} to the wire feeding dog b^{10} similar in every respect to the dog b^{10} already described and which is mounted to slide on a similar pair of vertically spaced rods b^{21} . At the outer end of the rods b^{21} is also a wire stop dog b^{13} similar in all respects to the dog b^{13} already referred to, it merely being reversely disposed. From the parts described it will be seen that by the rotation of cam b^5 , levers b^6 will be oscillated and the feeding dogs b^{10} at each side of the machine will be reciprocated. The feeding dogs b^{10} and b^{13} , as stated, have apertures therethrough through which the wire is fed and said apertures are, in the wire feeding operation, alined with the hardened tubes a^{29} and $a^{31'}$ carried in members a^{28} and a^{30} , respectively.

The shaft a^{44} , to which reference has already been made, passes laterally substantially between the levers b^6 and is supported at its outer end in a downwardly extending plate b^{22} , which is secured at the outer end of frame extensions projecting laterally from casing 8. The said shaft has secured thereto a cam b^{23} disposed substantially between the levers b^6 , which cam is disposed between and adapted to engage and move upstanding lugs b^{24} projecting upwardly from a rod b^{25} sliding in lugs carried by portions of the casing 8. The lower end of each of the levers b^6 is provided with a laterally extending lug b^6' having semicircular grooves formed at their inner sides in which the rod b^{25} is adapted to be moved. The rod b^{25} can be disposed so as to be between the ends of levers b^6 or to be moved into line with either of said levers. The cam b^5 is always stopped by the stop lug 52^a , already described, engaging the lug on lever 54 when the cam rollers on the levers b^6 are at the high parts of their cam tracks. When the rod b^{25} is thus moved into line with the levers b^6 they are held at such high or outer parts of the cam so that they are not oscillated thereby.

As already described, the shaft a^{44} carries the spaced cams a^{43} which move the slide a^{42} , which slide carries the head a^{45} in which the clinching parts are mounted. The shaft a^{44} also has secured thereto immediately outward of the slide a^{42} at the left of the ma-

chine, as seen in Fig. 10, a crank disk b^{26} having the outwardly projecting crank pin which movably engages the upper end of a lever b^{27} intermediately pivoted to the lower stationary portion a^{23} of the frame and having a slot at its lower end to engage over a pin b^{28} projecting outwardly from the side of slide a^{30} . The shaft a^{44} is provided at its right hand end, as seen in Fig. 2, with an operating handle b^{29} . When said shaft is oscillated by its handle lever, the rod b^{25} is moved to engage or disengage the lower ends of levers b^6 , the slide a^{42} is moved and the slide a^{30} is moved. The purpose of the movement of said slides will be later set forth.

The machine travels just above a work table 80 of T-shape in cross section, which work table extends longitudinally beneath the guiding rack 31 and will be supported on any suitable foundation, preferably a table 81 shown as carried on legs 82 in Fig. 1. The table 80 is adapted to be moved laterally, as indicated in Fig. 6.

As above stated, one particular use of the machine is for stapling together the slats and also the slats and a wooden strip on porch curtains. These curtains are formed on a loom and comprise slats connected together at spaced intervals by cords woven therebetween. The curtain is made in a continuous length on the loom and passes to the stapling machine where the slats extend lengthwise of the table, as shown in Fig. 1. Two of the slats x are folded with the sides in contact, as shown in Fig. 9 and positioned on top of the work plate or table 80. This plate has a narrow upstanding portion so that the adjacent slats of the curtain can fold down at either side thereof. The two slats x are first stapled together to form the bottom of the curtain. Fig. 9 shows these two slats already stapled and folded down at the left side of the work table 80. In this operation, the staples are merely inserted through two slats, such as the two narrow portions x shown at the left of the work table 80 in Fig. 9, the molding y not being stapled at this time. The machine, as a whole, will, at this time be disposed adjacent one end of rack 31, such as the right hand end, as shown in Fig. 1.

The roller 63 at the end of arm 62 will, at this time, be in contact with the bottom of the bar 45 and the cam shaft 52 is disengaged from the driving shaft 19. The motor 9 is started by the usual and convenient switch 12 and the gears 12 and 20 are rotated. The operator now grasps one of the handles 68 and pulls outwardly thereon, thus through the link 69, disengaging one of the pawls 70 and then swings the lever bar 67 to rotate rod 66 and through the link 65 and lever 24 throws the clutch 20, and the beveled gear 18^a is thus driven in a proper direction to traverse the machine to the left, as seen in Fig. 1. Through the rotation of the crank disk 28 by

the chain 23, the roller 30 moves in between the teeth 31^a and moves the machine to the left. With each rotation of shaft 26 on which crank disk 28 is mounted and while the 5 cam roller 30 is moving around the rounded bottom of teeth 31^a the cam 37, through lever 35 raises the slide 32 and applies the brake shoes 33^a so that the machine is intermittently held in stationary position. The movable 10 portion of the machine is easily traversed on the truck wheels 3. An intermittent traverse is thus given to the machine by the crank disk 28 and roller 30 engaging the rack teeth 31^a. The machine is usually started somewhat at 15 one end of the work. As soon as the roller 63 at the end of arm 62 passes the curved end of the bar 45 it is allowed to move upwardly. This, through the action of torsion spring 64, pulls up on the rod 59 and depresses the 20 wedge block 54^a on the lever 54, allowing the locking bolt 53 to be projected into the driving shaft 19 which connects the cam shaft 52 to said driving shaft. Said roller 63 after 25 passing the end of bar 46 is projected outwardly by a spring 63^b into the plane of bar 44 which is in the same plane as bar 46. Said cam shaft 52 then begins to revolve and the 30 stapling operation commences. Previous to the starting of the machine, the handle b²⁹ of shaft a⁴⁴ has been thrown in the proper direction to move rod b²⁵ into alinement with the lower end of the front lever b⁶. This lever is 35 thus thrown out of operation and only the wire feeding dog b¹⁰ at the left of the machine, as shown in Fig. 2, will be operated. This dog will be operated through the rear 40 lever b⁶, the arm b¹⁵, link b¹⁶, shaft b¹⁸ and arm b¹⁹. As the cam b⁵ revolves, said rear lever b⁶ will be oscillated and the feeding dog b¹⁰ will immediately feed forward a certain 45 length of the wire, the stop dog b¹⁸ operating to prevent rearward movement of the wire as the feeding dog b¹⁰ moves outward for a fresh grip on the wire. It may be here noted that when the handle b²⁹ is thrown, as stated, 50 the slide a⁴² is moved inwardly or toward the machine. This movement carries the head a⁴⁵ which is on said slide inwardly toward the work so that a narrow space is formed between the end of head a⁴⁵ and the front anvil a¹². This narrow space is suitable for the 55 stapling of the two slats x. At the same time, the slide a³⁰ is moved forward by the rotation of the shaft a⁴⁴ and the action of the crank disk b²⁶. The tube a³¹ in said slide is therefore moved into alinement with the apertures through the feeding dogs, and the radial edge of the swinging guiding member a³⁶ in said slide is substantially in alinement 60 with the axis of said tube. The throw of the feeding dog b¹⁰ is properly adjusted to feed the wire through the tube a³¹ and across the main forming anvil a¹¹ so that it projects beyond the anvil substantially the distance of 65 the width of the former a²¹ at the left of its slot a²², as shown in Figs. 11 and 12. As soon as the wire is thus fed across the ends of the main forming anvil a¹¹, as shown in Fig. 12, the former a²¹ is moved forward by its lever a¹⁹. As the former moves forward the wire 70 is severed by the cutting bar a³⁶ at the left, as shown in Fig. 14, which shears the wire off against the edge of tube A³¹. The wire is now bent about the anvils a¹¹ and a¹². As the former moves forward and thus bends the wire about said anvil, it pushes the swinging 75 guide member a³⁶ in slide a³⁰ backward, the same swinging from the full line position shown in Fig. 12 to the dotted line position shown in said figure. During this swinging movement the end of the wire which has been severed swings through the narrow slot a³⁷ in said guiding member and is thus prevented from any up-and-down movement. A 80 staple is thus perfectly formed and disposed in the grooves in the bending dies a²⁵ in the former a²¹. It may be here stated that stapling machines, as a rule, employ a special flat wire of considerable stiffness. This type of wire is necessary in the stapling machine of the prior art in order to form a perfect staple and prevent the staple from bending out of its plane when the wire is fed across in front of the former and later severed and bent. The present machine uses ordinary 85 round wire known as market wire. It was found that this wire would not form a perfect staple with the usual mechanism and the swinging feeding members having the narrow slots a³⁷ therein were thus provided. 90 With the use of these members the wire is kept in one plane as it is fed across the front of the former and a perfect staple can be formed of the ordinary round market wire. This improvement in the machine, therefore, 95 greatly reduces the cost of manufacturing the product. The market wire, after the staple is driven and clinched, is in every respect just as strong and efficient as the flat special staple wire and the cost of the market 100 wire is a great deal less than the cost of the special flat staple wire. As soon as the wire is fed across the main forming anvil a¹¹ the driving plunger a¹⁷ is moved forward and engages the wire and presses the same against 105 said anvil a¹¹. This action takes place before the former moves forward to bend and form the staple. As soon as the staple is formed over the anvils a¹¹ and a¹² the driving 110 plunger a¹⁷ is again moved forward by the cam a² and its levers a¹⁵ and a¹⁶. The staple is engaged by this driving plunger and moved forwardly. Just as the driving plunger commences the forward driving movement of the staple the cam a² through its lever a⁵ begins to elevate the main forming anvil a¹¹. Owing to the inclined or beveled shape of the 115 lower face of this anvil it is progressively withdrawn from the staple and the driving plunger a¹⁷ allowed to move forward. At 120 125 130

the same time, a guiding surface is provided by the sides of the receding beveled end of main forming anvil a^{11} so that the staple is held in perfect shape. When the main forming anvil a^{11} has been raised out of the staple its forwardly projecting portion comes into contact with the rearwardly projecting portion on auxiliary anvil a^{12} and this anvil is then progressively raised as the staple is moved forward and is lifted out of the staple just before the same is driven entirely into the work. It is thus seen that by successively lifting the anvils with the beveled lower ends, a guiding means is at all times provided for the staple, holding it properly in position during all portions of its driving movement. As the driving plunger a^{17} thus comes into contact with the work the lever a^{49} is operated by its cam a^4 . Owing to the lost motion connection of the end of this lever with the link a^{48} the link is not immediately depressed, the pin a^{50} being held upward as the lever moves downward by the springs a^{53} . The link a^{55} is therefore moved during the first movement of the lever a^{49} and the plunger a^{56} depressed. This plunger, through its lower wedge-shaped end, engages and moves forward the slide a^{54} so that the same is brought firmly against the work, as shown in Figs. 17 and 18. This movement takes place immediately after the machine stops between its intervals of travel on supports 1. The clinching anvil or plunger a^{57} is normally in the position shown in Fig. 18. Upon further movement of lever a^{49} the lost motion between it and link a^{48} is taken up and the clinching anvil or plunger a^{57} is now moved forward by the movement of link a^{48} and lever a^{17} . These movements of slide a^{54} and clinching anvil or plunger a^{57} take place while the cam roller on lever a^{49} moves over the first high part a^4 of the cam a^4 . The clinching anvil or plunger a^{57} is moved forward and projections $a^{57''}$ act on the inwardly extending lugs at the rear of the levers a^{58} so that the edged inwardly projecting ends $a^{58'}$ are swung inwardly, the intermediate lugs on the levers a^{58} at this time entering the recesses in the rear of the projection $a^{57''}$. As these end portions $a^{58'}$ swing inwardly, they engage the ends of the staple which has been driven through the work and swing said ends inwardly, as shown in Fig. 17, thus causing said ends of the staple to become crossed. After this initial movement of slide a^{54} and the clinching anvil or plunger a^{57} the lever a^{49} is acted upon by the high part $a^{4''}$ of cam a^4 and the clinching anvil or plunger a^{57} is given a quick further inward movement by the bell crank lever a^{17} . As the plunger a^{57} thus moves farther inwardly, the inwardly extending lugs at the rear of the levers a^{58} move into the recesses at the rear of the projections $a^{57''}$. The lugs at the intermediate portions of said levers are then cammed out-wardly by the beveled rear sides of the recesses at the rear ends of projections $a^{57''}$ so that ends $a^{58'}$ are again swung outwardly. The movement of the clincher anvil or plunger a^{57} now continues until it is pressed firmly against the staple and the ends of the staple are firmly pressed against the work, as shown in Fig. 13. The staple at this time is tightly clinched on the work by being pressed against both sides thereof by the plungers a^{17} and anvil a^{57} . As soon as the staple is thus tightly clinched in position, cam a^4 is rotated so that the lever a^{49} is swung upwardly by its actuating spring and lever a^{15} also is swung by its spring and the driving plunger a^{17} retracted. The former a^{21} is retracted in a similar manner so that the staple driving and forming parts are in their normal position ready for a repetition of the wire feeding and staple forming operation described. Trouble was sometimes experienced when the staple was driven through the wooden slats at a point where there was a knot or other hard portion of wood. One side of the staple would be deflected and pass through the slats and strike against the ends of the levers a^{58} . This would retard this side of the staple and the same would be pushed back into the groove in the side of the former a^{21} and the staple would be sheared at its rear corner against the plunger a^{17} . The side of the staple thus cut off would remain in the groove in the side of the former or the plate a^{25} . This wire would get out and be in the way of the wire fed for the next staple so that the feeding of the wire was interfered with and a jam of the wire would occur. In order to avoid this difficulty the semi-spherical ribs at the sides of the plunger a^{17} are provided. When the driving plunger a^{17} moves forward, these ribs move into the grooves in the former a^{21} at the sides of the slot a^{22} and one side of the staple cannot thus be pushed rearwardly into one of said grooves. The staple will be positively cleared from said grooves with each movement of the driving plunger. Attention is called to the fact that the staple is really being formed while the machine is in transit and the driving of the staple and the clinching thereof takes place while the machine is momentarily stopped. The intermittent traverse and stapling operation is repeated, the staples being driven with a spacing equal to the distance between the adjacent teeth 31^a of the rack 31. It may be stated that the staples are so spaced that they embrace and are clinched over the cords which hold the slats of the curtain together. The machine thus continues its travel to the left, as shown in Fig. 1, until the roller 63 on arm 62 comes into contact with the lower edge of the bar 44 at the left hand end of the rack 31. As the roller rolls against the rounded end of this bar it is depressed and the rod 59 is moved downwardly against the tension 130

springs 58 so that lever 24 is again moved to bring the wedge block 54^a again into engagement with the lock bolt 53 so that the cam shaft 52 is thrown out of operation by being uncoupled from the driving shaft 19. It will be noted that roller 63 was pushed out into the plane of bar 44, as previously stated. After being depressed by the rounded end of said bar said roller rolls along the bottom thereof until it reaches the wedge cam 43^a. Upon reaching this cam said roller is pushed in by the inclined face thereof against the pressure of spring 63^b until it is brought into the plane of bar 43 and inside of bar 44. When said roller is thus pushed inwardly it springs up with arm 62 into contact with the lower surface of bar 43. This operation is necessary owing to the fact that it is desired to stop the operation of the cam shaft 52 and the staple forming and driving mechanism at a different point in the travel of the machine from that at which said mechanism is thrown into operation. If only one bar were used in place of two bars 43 and 44 and the staple forming and driving mechanism was thrown out of operation at the same place that it is thrown in, a staple would be formed and ejected which would not pass into the work and would thus be wasted. In order to avoid this the said mechanism is stopped at a point further toward the center of rack 31 than the point at which it is thrown into operation. The stapling and wire feeding mechanism is now stopped and the cam 52 stopped with the rollers on the levers 56 at the high part of the cam tracks, this position being determined by the stop lug 52^a engaging the stop on lever 54. The disk 28 continues to revolve and move the machine to the left until one of the rollers on the pins 75^a substantially engages with the arm 51. At just about this same instant the pin 29^b comes into engagement with the arm 51^b. The pin cams along the inner side of said arm and moves the same outwardly. This swings arm 51 inwardly and moves the bar 74 longitudinally. This movement through the arm 72 oscillates the shaft 66 which is connected to and moves the main clutch lever 24, thus moving the clutch 20 to stop the machine. Clutch 20 is thus moved to neutral position and locked therein by the lever 70. It will be noted that at this time the roller 30 is moving about the end of one of the teeth 31^a and the brake 33^a is applied to the channel member 1. The clutch is thus thrown out while the machine is in stationary position and any jumping of the machine is prevented. All danger of breaking the clutch teeth is thus also eliminated. Furthermore, it is necessary to stop the machine in this manner in order to keep the roller 30 synchronized with the rack teeth. If the clutch were thrown out while the machine is in motion the traveling motion might substantially disarrange the proper relative posi-

tion of the roller 30 and the rack teeth 31^a. The machine is now stopped at the left hand end of rack 31, as seen in Fig. 1. The curtain is now advanced over the work table 80 and the next two slats folded up with their sides in contact, as shown in Fig. 9. The operator now shifts the work table 80 to the position shown in Fig. 9, or from the full line position shown in Fig. 6 to the dotted line position shown therein. The molding y is now placed along side of the slats x in position to be stapled thereto. Before the machine starts its traverse to the right, the handle b²⁹ will again be turned to position the parts for the longer staples. By this movement of the handle and the shaft a⁴⁴, rod b²⁵ will be moved by the cam b²³ and will now move into alignment with the lower end of the rear lever b⁶ so that this lever and the feeding dog b¹⁰ at the left of the machine will be held out of operation. At the same time, the slide a⁴² will be moved forwardly, thus moving the head a⁴⁵ forwardly and widening the space between the parts thereof and the auxiliary or forward anvil a¹² so as to afford a wider space to accommodate the molding y. At the same time, the crank disk b²⁶ will act on the lever b²⁷ and move slide a³⁰ rearwardly. This slide moves to the position shown in dotted lines in Fig. 12 and to the position shown in full lines in Fig. 11. A space is thus formed between the block a⁶³ and the slide a³⁰. The purpose of moving the slide a³⁰ rearwardly is to give room for the wire to be fed past the former a²¹ to form the longer staple, as will presently appear. The machine is now adjusted to form and drive the longer staples and started to the right and as soon as the roller 63 on arm 62 moves over the curved end of bar 43 the cam shaft 52 will be connected to the driving shaft 19 and the staple forming and driving mechanism again thrown into operation, as already described. The machine will now feed wire by the feeding dog b¹⁰ at the right, as shown in Fig. 2. This feeding dog will be reciprocated so that it will feed a long length of wire, which wire will be fed through the said dog and through the tube a²⁹ in block a²⁸. This wire will be fed in the rear of the main forming anvil a¹¹ and will pass to the left of the slot a²² in the former a²¹, the same distance as the distance between said slot and the right hand face of said former, as shown in Fig. 11. It will be seen that if slide a³⁰ were in its forward position, the wire would be fed across into the tube a³¹ and would be severed by the cutting bar a²⁶ at the left side of the machine, as seen in Figs. 11 to 15. The slide a³⁰, therefore, is moved rearwardly so that a free space is afforded for the wire projecting beyond the left hand face of former a²¹. The wire is fed through the swinging guiding member a³⁶ in the block a²⁸ and is guided therein when the former a²¹ moves forward to form the staple

in the same manner as already described for the swinging guiding member a^{36} which is in the slide a^{30} . The operation of forming and driving the staple is now completed in the 5 same manner as already described and the machine continues to travel to the right and drives and clinches the staples at spaced intervals until roller 63 engages the curved end of bar 46. Said roller will now be depressed and 10 the cam shaft 52 will be stopped and the staple forming and driving mechanism thrown out of operation, as previously described in connection with bar 44. When roller 63 reaches wedge cam 45^a, which is similar to wedge cam 15 43^a, it will be moved inwardly in the plane of the bar 45 and will swing up against the bottom thereof and travel on said bar. It will be noted that roller 63 will then be in position to be operated in its next travel to 20 the left when it reaches the end of bar 45. The travel to the right continues until pin 29^b engages the face of arm 51^b. Said pin slides along the face of said arm 51^b and swings arm 51^a to move bar 74 and again dis- 25 engage the clutch 20, as previously described. A different shape of arm 51^b is necessary at the right hand side of the machine in order to avoid striking the curved arm 62. The machine is thus stopped at the end of its travel to 30 the right and the two slats x , together with the molding y have then been stapled together. It may be stated that after this operation, the strings connecting the slats are severed between the folded and stapled slats x 35 which are folded down, as seen at the left of work table 80 in Fig. 9, and the slats x and molding y shown at the right of said work table 80. The part at the left of the work table, as seen in Fig. 9, forms the bottom of 40 one curtain and the part including the two slats x and the molding y forms the top of the other curtain. The curtain, it will be seen, can be made of any length desired and can also be trimmed to have any desired 45 width.

It will be seen that the plate 40 can be adjusted to various positions, as already described, so that the travel of the machine can be properly determined for different lengths 50 of curtains or other material. The cam shaft can be quickly thrown out of operation from the front of the machine at any time by the operator merely pulling up on the front end of lever 54 which projects at the front of the 55 machine and the travel of the machine can be manually stopped or reversed at any time by the operator manipulating the handle 68 on lever bar 67. The handle 68 and bar 67, however, normally are locked against movement 60 by the pawl lever 70.

The adjustment provided for the lower end of the levers a^5 , a^{15} and a^{19} is of great utility in securing the desired operation of the parts. A very accurate operation is necessary in 65 forming and driving the staples and a small

difference in the cam surface or adjustment makes quite a difference in the movement of the parts. By providing the angular adjustment at the end of said levers a very exact and accurate operation is obtained.

From the above description it is seen that applicant has provided a machine having great utility in driving and clinching a series of spaced staples through a considerable length of work. The machine has been in 70 actual operation for some time in securing together the parts of the curtains, as stated, and the operation of the machine is very rapid and accurate. The perfection of the machine was only arrived at after a great many trials 75 and difficulties and after the mechanism was repeatedly changed. As above stated, the machine uses ordinary round market wire for forming the staples and a very perfect and perfectly placed and clinched staple is produced from this wire. The machine is easily manipulated and largely automatic in 80 operation.

It will, of course, be understood, that various changes may be made in the form, details, 85 arrangement and proportions of the parts without departing from the scope of applicant's invention, which, generally stated, consists in a device capable of carrying out the objects above set forth, such as shown and 90 described and defined in the appended 95 claims.

What is claimed is:

1. A stapling machine having in combination, a support, a staple forming, driving and clinching mechanism longitudinally movable thereon, and means for imparting to said mechanism successively, a plurality of movements in one direction and actuating the same to drive and clinch a staple after each movement.

2. A stapling machine having in combination, a support, a staple forming and clinching mechanism longitudinally movable intermittently therealong, said mechanism including means to form a staple while said mechanism is moving on said support and to drive and clinch the staple while said mechanism is stationary on said support.

3. A stapling machine having in combination, a support, a staple forming, driving and clinching mechanism movable longitudinally along said support, and means for imparting to said mechanism successively a plurality of movements in either direction on said support and actuating the same to drive and clinch a staple after each movement.

4. A stapling machine having in combination, a support, a rack secured to said support having spaced teeth with rounded ends, a frame carrying a staple forming, driving and clinching mechanism, a revoluble member on said frame carrying a roller adapted to engage said teeth and intermittently move said frame, and means for actuating said rev-

oluble member and said staple forming, driving and clinching mechanism.

5. The structure set forth in claim 4, the radius of the rounded ends of said teeth being the same length as the radius of the path of the inner side of said roller, whereby said roller will move said frame when it engages the sides of said teeth but will not move said frame while it is passing around the rounded 10 ends of said teeth.

6. A stapling machine having in combination, a support, a frame movable on said support carrying a staple forming, driving and clinching mechanism, a driving means on said frame, means for traversing said frame on said support, means for actuating said staple forming, driving and clinching mechanism, connecting and disconnecting means for said last mentioned means and said driving means, 20 and adjustable means on said support for actuating said connecting and disconnecting means.

7. The structure set forth in claim 6, connecting and disconnecting means for said 25 traversing means and said driving means, and means carried by and adjustable with said adjustable means for operating said last mentioned connecting and disconnecting means.

8. A stapling machine having in combination, a support, a frame movable on said support carrying a staple forming, driving and clinching mechanism, a driving means on said frame, means for traversing said frame on said support, means for throwing said staple 35 forming, driving and clinching mechanism into operation to form, drive and clinch staples in succession after said frame has traversed a certain distance on said support, means for throwing said mechanism out of 40 operation when said frame nears the other end of said support, and means for stopping said traversing means when said frame nears the other end of said support.

9. A stapling machine having in combination, a support, a frame carrying a staple forming, driving and clinching mechanism movable on said support, means imparting movement to said frame at regular intervals on said support, a brake mechanism on said 50 frame, and means for actuating said brake mechanism between the movements of said frame to hold said frame in fixed position.

10. A stapling machine having in combination, a support, a frame carrying a staple forming, driving and clinching mechanism movable on and depending from said support, a work supporting table below said frame, and means for intermittently traversing said 55 frame on said support and driving and clinching staples at regular intervals in work supported on said work table.

11. A stapling machine having in combination, a work supporting means, a support substantially vertically alined with said work supporting means, a mechanism independent-

ly movable along said support including means for forming, driving and clinching a staple, said staple being driven in a substantially horizontal plane and substantially at right angles to the line of travel of said mechanism, and means for moving said mechanism along said support in a series of steps and actuating said means to drive and clinch a staple after each step.

12. A stapling machine having in combination, a track, a frame carrying a staple forming, driving and clinching mechanism longitudinally movable thereon and depending therefrom, and means for moving said frame along said track equal distances at regular intervals, means for locking said frame in stationary position after each movement, means for actuating said mechanism to drive a staple while said frame is in stationary position, and a work support beneath said frame and mechanism and parallel to said track whereby work may be moved beneath said machine and transversely of said support and the line of travel of said mechanism.

13. A staple forming, driving and clinching mechanism, means at one side thereof for feeding one length of wire thereto to form one length of staple, means at the other side thereof for feeding a different length of wire in the opposite direction to form a different length of staple, a work engaging member, means for positioning the same in different positions to suit the width of work and the length of the staple driven, and means for operating said mechanism and one of said feeding means.

14. A staple forming mechanism comprising an anvil, means for feeding a wire at one side of said anvil, a former co-operating with said anvil adapted to sever said wire and bend the same around said anvil, and means for guiding said wire and retaining the same in the proper plane during said feeding and bending movement, said last mentioned means comprising a movable member having a narrow slot therein through which said wire moves in its feeding movement towards said anvil.

15. A staple forming mechanism comprising an anvil, means for feeding a wire at one side of said anvil, a former co-operating with said anvil adapted to sever said wire and bend the same around said anvil, and means for guiding said wire and retaining the same in the proper plane during said feeding and bending movement, comprising a swinging member having a narrow slot therein, into which the wire is fed and through which it swings, said member being swung out of the way as the former advances over said anvil.

16. A stapling mechanism comprising an anvil, means for feeding a wire at one side thereof, a former adapted to co-operate with said anvil to sever said wire and bend the end portions of the wire around said anvil, and

a swinging member disposed in front of said former and at one side of said anvil and having a narrow slot therein through which the wire swings in its bending movement, said member being adapted to be swung to one side by said former as it advances to embrace said anvil.

17. A staple forming and driving mechanism comprising an anvil having a forwardly and downwardly inclined lower end, an auxiliary anvil in front of and engaging said anvil also having a forwardly and downwardly inclined lower end, means for forming a staple over said anvils, a driving plunger adapted to advance and move said staple, and means for successively raising said anvils rectilinearly in the same direction as said driving plunger advances whereby said anvils are gradually and successively moved out of said staple and said staple is constantly guided thereby.

18. A staple forming mechanism comprising an anvil, a member at each side thereof having a wire guiding tube therein, means at the outer sides of said members for feeding wire through said tubes and at the rear of said anvil, and means for moving one of said members rearwardly whereby it is moved out of the way of the wire fed through the tube in the other member.

19. The structure set forth in claim 18, means for throwing out of operation one of said wire feeding means, and a common means for operating said last mentioned means and said second mentioned means.

20. The structure set forth in claim 18, means for throwing out of operation one of said wire feeding means, a work contacting member movable forwardly and rearwardly to accommodate work of different thicknesses, and a common means for moving said work contacting member and actuating said last mentioned means and said second mentioned means.

21. In a stapling machine, a cam shaft, a plurality of cams thereon and rotatable therewith, an anvil, a lever engaging said anvil and carrying a roller engaging one of said cams, a former, a lever engaging said former and carrying a roller engaging another of said cams, a driving plunger, a lever engaging said plunger and carrying a roller engaging still another of said cams, said cams being arranged to move said former forward over said anvil successively to form the staple, to raise said anvil and to move said driving plunger forward to drive said staple, two of said levers having relatively movable parts whereby the timing of the movements of said anvil, former and driving plunger may be varied.

22. The structure set forth in claim 21, a work clamping member, a clinching plunger, and a lever operatively connected to said work clamping member and connected to said

clinching plunger by lost motion connection and carrying a roller contacting still another of said cams whereby said work contacting member is first advanced against the work and said clinching plunger is then moved forward to clinch the staple.

23. In a stapling machine, a cam shaft, a cam thereon, a member adapted to operate on a staple, and a lever connected to said member and operated by said cam, said lever having an arm with an end portion connected thereto angularly adjustable relatively to said arm and adapted to be rigidly secured to said arm, said end portion operatively engaging said member.

24. In a stapling machine, means for forming a staple and driving the same through the work, opposed swinging means for bending and crossing the ends of said staple after the same have been fully projected through the work, and a clinching plunger for actuating said means in opposite directions after the staple ends are fully projected through the work and for subsequently clinching said ends against the work.

25. The structure set forth in claim 24, said second mentioned means comprising oppositely disposed levers, and means on said clinching plunger for actuating said levers to bend and cross said ends as said plunger moves into clinching position.

26. A stapling machine having in combination, a support, a frame movable on said support carrying a staple forming, driving and clinching mechanism, means for traversing said frame along said support in a series of steps, automatic means for stopping the traverse of said frame, and manually operated means for stopping or reversing the travel of said frame on said support at will.

27. A stapling machine having in combination, a support, a staple forming driving and clinching mechanism progressive along said support, means for progressing said mechanism along said support in a series of steps, automatic mean for actuating said mechanism to form, drive and clinch staples at intervals and to stop said mechanism, and manual means for throwing said mechanism into or out of operation at will.

28. A stapling machine having in combination, a support, a frame carrying a staple forming, driving and clinching mechanism movable on said support, a brake mechanism on said frame adapted to engage said support to hold said frame in fixed position, and a revoluble member having means thereon for intermittently traversing said frame on said support and also having means thereon for applying said brake between the traversing movements of said frame.

29. A stapling machine having in combination, a support, a frame carrying a staple forming, driving and clinching mechanism movable on said support, a brake mechanism

on said frame adapted to hold said frame in fixed position, and a common means for moving said frame on said support at intervals and actuating said brake between said intervals of movement.

30. A stapling machine having in combination, means for forming and driving a staple through the work, a member adapted to contact the work to hold it in position to receive 10 said staple, a plunger adapted to clinch the ends of said staple, and a cam-operated lever for moving said work engaging member against the work and subsequently actuating said clinching plunger.

31. The structure set forth in claim 30, a member connected intermediately to said lever having a beveled lower front portion adapted to engage said work engaging member and move the same forward, and a lever 20 having a lost motion connection with said first mentioned lever engaging said clinching plunger and adapted to move the same forward on the subsequent movement of said first mentioned lever.

32. In a stapling machine, means for driving a staple through the work, a movable clinching member, and means for crossing the ends of said staple after being fully projected through the work comprising opposed 30 levers having cam portions thereon at each side of their pivots, said clinching member having cam portions thereon co-operating with said cam portions on said levers.

33. A stapling machine having in combination, a support, a frame movable on said support carrying a staple forming, driving and clinching mechanism, a rack fixed to said support, means on said frame engaging said rack to move said frame intermittently longitudinally of said support, and means for actuating said staple forming and driving and clinching mechanism to form and drive staples at regular intervals.

34. A staple forming mechanism comprising an anvil, means for feeding a wire at one side of said anvil, a forming mechanism co-operating with said anvil adapted to receive said wire and bend the same around said anvil, and swinging means for embracing and guiding said wire and retaining the same in one plane during said feeding and bending movements.

35. A stapling machine having in combination, means for bending a wire to form a staple, and swinging means embracing and 55 guiding the end of said wire during the bending movement, which end forms a leg of the staple.

36. A staple forming mechanism comprising an anvil, means for feeding a wire at one side of said anvil, a former co-operating with said anvil to bend said wire around the anvil to form a staple, and means engageable and movable by said former, having a narrow slot 60 therein for receiving and retaining the wire 65 in one plane during its bending movement.

37. In a stapling machine, an anvil, a former, means for feeding a wire across said anvil and former, means for moving said former to bend said wire about said anvil, and a member oscillatable about an axis at right angles to the movement of said former and having a recess therein for receiving said wire and holding the same in one plane during 70 said bending movement.

38. In a stapling machine, an anvil, a former, means for feeding a wire across said anvil and former, means for moving said former to bend said wire about said anvil, and a member having a recess therein for receiving said wire and holding the same in one plane during said bending movement, said last mentioned member being oscillated during 80 said bending movement.

In testimony whereof I affix my signature.
ZACHARY E. RUSSELL.
